UNITED STATES PATENT OFFICE

109,756

DESIGN FOR A SMOKING PIPE

Alex E. Lookholder, La Grange, Ill.

Application March 4, 1938, Serial No. 75,566

Term of patent 14 years

To all whom it may concern:

Be it known that I, Alex E. Lookholder, a citizen of the United States, residing at La Grange, in the county of Cook and State of Illinois, have invented a new, original, and ornamental Design for a Smoking Pipe, of which the following is a specification, reference being had to the accompanying drawing, forming part thereof,

In the drawing:

Fig. 1 is a side elevation of a smoking pipe showing my new design.

Fig. 2 is a plan view of the same.

I claim:

The ornamental design for a smoking pipe as shown.

ALEX E. LOOKHOLDER.
